UNITED STATES PATENT OFFICE.

WALTER D. WOOD, OF NEW YORK, N. Y.

FEEDING AND BURNING FINE FUEL.

1,185.156.

Specification of Letters Patent.

Patented May 30, 1916.

Application filed April 17, 1914. Serial No. 832,524.

To all whom it may concern:

- Be it known that I, WALTER D. Wood, a citizen of the United States, residing in the borough and county of Richmond, city and State of New York, have invented certain new and useful Improvements in Feeding and Burning Fine Fuel, of which the following is a specification, reference being had therein to the accompanying drawing.
- 10 This invention refers to certain new and useful improvements in mechanism for feeding and burning powdered fuel, such as coal dust, pulverized coal, and similar substances.
- The object of the invention is to provide improved and simplified means for mixing air with the comminuted fuel and feeding the composition forward under pressure to the furnace where it is to be burned, besides adding to the fuel carrier in its transit a supplemental amount of fresh air which will improve the inflammable quality of the mixture and enable the proper requirements for rapid and successful burning in the furnace to be met more efficiently.
- 15 The invention comprises a mixing chamber with means for supplying air thereto, in combination with fluid pressure means for transmitting the mixture to the furnace, and auxiliary means for combining with the first
- 20 mixture a second quantity of air; and it also comprises various details and peculiarities in the construction, arrangement and combination of the various parts, substantially as will be hereinafter described and then
- 25 more particularly pointed out in the claims.
- In the accompanying drawing illustrating my invention, Figure 1 is a top plan view of my improved mechanism for mixing fine fuel and feeding it forward to the
- 30 furnace, together with means for supplying extra air thereto, with the screw feeding device omitted. Fig. 2 is a vertical section of the same, including the screw feeding device, the screw of which is in side view.
- 35 Similar characters of reference designate corresponding parts throughout the different figures of the drawing.
- The mixing chamber wherein air and coal dust are commingled in proper proportions, 40 agitated and delivered to the transmitting air blast, consists of a conical hopper 6, to which the fuel is fed from the bin 1 by means of a feed screw 2, on a shaft 3, mounted in a housing 4, having a spout 5 through
- 45 which the powdered material is fed into the chamber 6. Said chamber delivers into

a pipe 8, through which an air blast is passing, and said pipe has a flaring end 9, which is contained within an inclosing cylinder 18 that is adapted to be introduced into the 60 wall of the furnace where the fuel is to be burned.

In my present improvements, I furnish the air which is to mix with the coal and then to be propelled through the pipe 8 to 65 the delivery nozzle of the furnace from some suitable high pressure source, as for instance, an air reservoir from which a pipe 17 leads to my apparatus. Pipe 17 preferably connects with a line of pipe 15, which is provided at one end with a nozzle 13, close to which is a valve 14 by means of which the air can be turned on or shut off from the nozzle 13. Nozzle 13 blows air into a conical pipe 12, which is supported within 70 another similar conical pipe 10, that is held within the flaring end 11 of the main fuel pipe 8. Thus it will be seen that the pipes 10 and 12 furnish an injector mechanism which receives the air jet from nozzle 13 75 and allows atmospheric air to be drawn in between pipes 10 and 12 and between nozzle 13 and pipe 12, so that a strong air blast is created and driven forward through the pipe 8. When it passes the lower end of 80 the conical mixing chamber 6, it absorbs the combined air and dust falling from said chamber and increases the mixture by adding more air to the dust, and the current of air and dust thus formed is swept forward 85 with great rapidity and pressure through the entire length of pipe 8 until it reaches the cylinder 18 and is discharged thereinto through the flaring end 9 of pipe 8, the purpose of this flaring end being to reduce the 90 velocity.

The conical chamber 6 not only receives the fuel fed thereto from the spout 5 on the underside of the housing 4, but it also receives air from the discharge nozzles of the 100 pipes 7, 7 which connect with the main supply 15, and are each preferably provided with cocks or valves 16 for turning the supply on and off. Thus oppositely directed streams of air enter the interior of the hopper 6. They are opposite from each other so as not to directly impinge upon each other, and hence they impart a circular rotary motion to the fuel. The air combines with the powdered material, and this forcible entry of the air is capable of breaking up aggregations, lumps, and damp masses of 105 110

dust, which may be therein, and making an intimate and suitable mixture.

The cylinder 18 already mentioned, which receives the flaring end of the pipe 8, is perforated laterally with openings 23, to which are fixed conical rings or pipes 19, in which are supported conical pipes 20, there being annular spaces between the pipes 19 and 20. The smaller pipes 20 receive air current from the discharge ends 21 of pipes that are connected with the main supply pipe 15, there being a cock or valve 22 to control passage of the air through the discharge ends 21. When the air is turned on and allowed to emerge from the ends 21, it will blow through the rings or pipes 19 and 20 and cause a strong suction and draw in a quantity of atmospheric air, and by this injector mechanism air will be supplied to the cylinder 18, said air being for the purpose of combustion and being termed combustion air. Its amount will be regulated by the pressure of the air blast from the discharge ends 21 and also by the construction of the concentric conical rings 19 and 20. Thus while the main nozzle consisting of the concentric pipes 8 and 18 receives a supply of fuel carried thereto under a pressure sufficient to transmit the fuel to the nozzle, it will be evident that said nozzle receives likewise an auxiliary supply of air whose function it is to promote combustion in the furnace, and this combustion air will be added to the carrying air inside the duplex nozzle, or inside the furnace, as the case may be, the union taking place while the stream of fuel-laden air is coursing through the duplex nozzle and entering the wall of the furnace. Thus by the use of a stream of air generated at some distant point or stored in a reservoir and drawn upon for the purpose, it will be manifest that I am able to organize a fuel-laden vehicle which will pass on rapidly to the furnace and to add to such carrying air a plenteous supply of combustion air which will be fresh and effective so that the best possible results in the rapid production of a hot and terrific flame will be brought about, and I desire to claim that I may make a large number of changes in the precise details of my invention within wide limits of construction and operation without varying from the spirit of the invention, or exceeding the fair scope entitled to be given to the claims.

Having thus described my invention, what I claim as new and desire to secure by Letters Patent, is:

1. In a device of the class described, the combination with a mixing chamber, of a passage leading therefrom, means for causing an air blast to enter one end of said passage to provide fuel-carrying air, means for supplying air under pressure at the dis-

charge end of said passage, said means comprising a pair of inlet pipes diametrically opposed to each other so that the two streams of air therefrom will commingle and thoroughly break up the stream of fuel laden air, and means for supplying air for the two purposes from a common source.

2. In a device of the class described, the combination with a chamber for commingling air and fuel, of a passage receiving the commingled air therefrom, an injector for introducing air into one end of the passage, another injector for supplying air to the fuel-laden air as it emerges from said passage, said latter injector consisting of two pipes situated diametrically opposite to each other so that the two streams of air issuing therefrom will commingle and thoroughly break up the stream of fuel laden air.

3. In a device of the class described, the combination with a chamber for commingling air and fuel, of a passage receiving the commingled air therefrom, an injector for introducing air into one end of the passage, another injector for supplying air to the fuel-laden air as it emerges from said passage, said injector consisting of two pipes diametrically opposed to each other so that the two streams of air issuing therefrom will commingle with each other and thoroughly break up the stream of fuel laden air emerging from said passage, and means for supplying air under pressure to both injectors from a common source.

4. In a mechanism for feeding and burning fine fuel, the combination with an agitating chamber wherein the powdered fuel is stirred and mixed with air, of a passage conveying air and fuel from said chamber, an injector for introducing air into one end of said passage, a second injector for supplying combustion air at the other end of said passage, said injector consisting of two pipes diametrically opposed to each other so that the two streams of air issuing therefrom will commingle with each other and thoroughly break up the stream of fuel laden air emerging from the end of said passage, means for introducing air into the agitating chamber, and means for supplying air from a common source under pressure for the three purposes.

5. In a device of the class described, the combination with a chamber for agitating and mixing fuel and air, of a pipe receiving the mixture from said chamber, an injector delivering air to one end of said pipe, a nozzle cylinder receiving the other end of said pipe, an injector delivering air into said nozzle cylinder for use as combustion air with the fuel-laden current coming through the pipe, said injector consisting of two pipes diametrically opposed to each other so that the two streams of air issuing therefrom will

commingle and thoroughly break up the stream of fuel laden air emerging from the pipe, and suitable pipe means for delivering air to the agitating chamber.

6. In a device of the class described, the combination of a conical, agitating and mixing chamber, means for feeding fine fuel thereto, a pipe receiving the commingled air and fuel from said chamber, air inlet means for said chamber, means for introducing a blast of air into one end of the said pipe for transporting the fuel to the end of the latter, a nozzle cylinder surrounding said latter end and receiving the fuel-laden air discharged thereinto, means for introducing air under pressure into said cylinder for use as combustion air with the fuel-laden current, said means consisting of a pair of pipes situated diametrically opposite to each other so that the two streams of air issuing therefrom will commingle and thoroughly break up the stream of fuel laden air, all substantially as described.

7. In a device of the class described, the combination with a mixing chamber, consisting of a conical-shaped hopper, means for introducing air under pressure into said hopper, said means consisting of two pipes inserted in the sides of said hopper diametrically opposite to each other, but fixed in direction so that the two streams of air from the two pipes will not commingle by a direct impingement upon each other, but will pass each other in parallel lines so as to thoroughly break up the stream of fuel laden air entering the hopper, a passage leading from said mixing chamber, means for causing an air blast to enter one end of said passage to provide fuel-carrying air, means for supplying air under pressure at the discharge end of said pipe, and means for supplying air for the three purposes from a common source.

8. In a device of the class described, the combination with a mixing chamber for commingling air and fuel, said chamber consisting of a conical-shaped hopper, means for introducing air under pressure into said hopper, said means consisting of two pipes entering the sides of the hopper opposite to each other, but fixed in direction so that the two streams of air issuing therefrom will not directly impinge upon each other but will pass along parallel lines a short distance apart so that the effect of the air blast will be to break up the stream of fuel entering the hopper, a passage receiving the commingled air and fuel from the chamber wherein it is mixed, an injector for introducing air into one end of said passage, and another injector for supplying air to the fuel-laden air as it emerges from said passage.

9. In a device of the class described, the combination with a chamber for commingling air and fuel, said chamber consisting

of a conical-shaped hopper, means for introducing air under pressure into said hopper, said means consisting of two pipes entering the sides of the hopper at opposite points, but fixed in direction so that the two streams of air delivered thereby will pass in parallel lines without directly impinging upon each other, and will have the effect of blowing or deviating the stream of fuel entering the hopper so as to thoroughly break it up, a passage receiving the commingled air and fuel from the chamber wherein they are mixed, an injector for introducing air into one end of the said passage, another injector for supplying air to the fuel-laden air as it emerges from said passage, and means for supplying air under pressure to both injectors from a common source.

10. In a mechanism for feeding and burning fine fuel, the combination of an agitating chamber wherein the powdered fuel is stirred and mixed with air, said chamber consisting of a conical-shaped hopper, means for introducing air under pressure into said chamber, said means consisting of two pipes entering the sides of said hopper at opposite points, but fixed in direction so that the two streams of air therefrom will pass along parallel lines a short distance from each other without directly impinging on each other so that the stream of fuel entering the hopper may be thoroughly broken up, a passage conveying air and fuel from said agitating chamber, an injector for introducing air into one end of said passage, a second injector for supplying combustion air at the other end of said passage, and means for supplying air from a common source under pressure for the three purposes named.

11. In a device of the class described, the combination of a chamber for agitating and mixing fuel and air, said chamber consisting of a conical-shaped hopper, means for introducing air under pressure into said hopper, said means consisting of a pair of inlet devices entering the sides of said hopper at points substantially opposite, but fixed in direction so that the two streams of air delivered therefrom shall pass along parallel lines without directly impinging on each other so that the stream of fuel entering the hopper may be thoroughly broken up, a pipe or passage receiving the mixture from said agitating chamber, an injector delivering air to one end of said pipe, a nozzle cylinder receiving the other end of said pipe, an injector delivering air into said nozzle cylinder for use as combustion air with the fuel-laden current coming through the pipe.

12. In a device of the class described, the combination of a conical agitating and mixing chamber, means for feeding fine fuel thereto, means for introducing air under

- pressure into said mixing chamber, said means consisting of two inlet pipes entering the sides of said hopper at substantially opposite points, but fixed in direction so that
- 5 the two streams of air delivered thereby may pass along separate lines at a short distance from each other without directly commingling so that they will have the effect of breaking up the stream of fine fuel entering
- 10 the hopper, a pipe receiving the commingled air and fuel from said agitating and mixing chamber, means for introducing a blast of air into one end of the said pipe for transporting the fuel to the end of the latter, a
- 15 nozzle cylinder surrounding said latter end and receiving the fuel laden air discharged thereinto, means for introducing air under pressure into said cylinder for use as combustion air with the fuel laden current, all
- 20 substantially as described.
13. In a device of the class described, the combination with a mixing chamber, consisting of a conical-shaped hopper, means for introducing air into said mixing chamber, consisting of two pipes entering the
- 25 sides of said hopper at substantially opposite points so that the two streams of air delivered therefrom will pass along parallel lines closely contiguous to each other so as to produce a breaking up effect on the stream of entering fuel, a passage leading from the said mixing chamber and receiving commingled air and fuel therefrom, means for causing an air blast to enter one end of said passage to provide fuel carrying air, means for supplying air under pressure at the discharge end of said passage, said means comprising two pipes diametrically opposed to each other so that the two streams of air issuing therefrom will commingle and thoroughly break up the stream of fuel laden air, and means for supplying air for the three purposes from a common source.
- In testimony whereof I affix my signature in the presence of two witnesses.
- WALTER D. WOOD.
